US0D1110125S

(12) **United States Design Patent** (10) **Patent No.:** **US D1,110,125 S**
(45) **Date of Patent:** **** Jan. 27, 2026**

(54) **SCOOP UTENSIL**

(71) Applicant: **Glenwood Bio-Analytics Ltd.**, Boulder, CO (US)

(72) Inventor: **Samuel Abraham Steingard**, Boulder, CO (US)

(73) Assignee: **Glenwood Bio-Analytics Ltd.**, Boulder, CO (US)

(**) Term: **15 Years**

(21) Appl. No.: **29/940,081**

(22) Filed: **Apr. 30, 2024**

(51) **LOC (15) Cl.** **07-04**

(52) **U.S. Cl.**

USPC **D7/691**

(58) **Field of Classification Search**

USPC D7/368, 642, 653, 669, 688, 691;

D10/46.2; D27/172, 184, 193, 194

CPC A47G 21/04; A47J 43/28; A47J 43/281;

(57) **CLAIM**

The ornamental design for a scoop utensil as shown and described.

DESCRIPTION

FIG. 1 is a perspective view of a first embodiment of a scoop utensil showing my new design;

FIG. 2 is a bottom perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a perspective view of a second embodiment of a scoop utensil showing my new design with oblique line surface shading that illustrates a transparent surface;

FIG. 10 is a bottom perspective view of the scoop utensil of FIG. 9;

FIG. 11 is a front elevation view of the scoop utensil of FIG. 9;

FIG. 12 is a rear elevation view of the scoop utensil of FIG. 9;

FIG. 13 is a right elevation view of the scoop utensil of FIG. 9;

FIG. 14 is a left elevation view of the scoop utensil of FIG. 9;

FIG. 15 is a top plan view of the scoop utensil of FIG. 9; and,

FIG. 16 is a bottom plan view of the scoop utensil of FIG. 9.
